CARRIER ROD DRIVING MECHANISM FOR
KNITTING MACHINESCharles R. Fegley, Laureldale, Pa., assignor to
Textile Machine Works, Wyomissing, Pa., a
corporation of Pennsylvania

Application February 1, 1952, Serial No. 269,499

8 Claims. (Cl. 66—126)

1

This invention relates to yarn carrier rod drive mechanism for full-fashioned knitting machines and more particularly to a positive drive means supplementing the conventional friction drive for the carrier rods of such machines.

In full-fashioned knitting machines, yarn is fed to the needles by one or more yarn carriers, the main carrier or carriers being reciprocated in opposite directions across the full width of the fabric knitted. The main carriers are carried on rods which are driven by friction boxes having frictional engagement with a friction rod driven at full speed. The limit of movement of the main yarn carrier rods and friction boxes is controlled by end stops operated by usual narrowing head devices of the machine. The full speed friction rod has a greater travel than the friction boxes and during the latter portion of said travel, the rod slides through the friction boxes while the boxes are stationary. This relative sliding movement causes wear between the parts resulting in a relative slipping movement between the friction rod and boxes, particularly at the start of the movement of the boxes. However, it is essential that the friction boxes start with the friction rod in order to maintain a pre-determined operating relation between the boxes and a shock absorber mechanism, the latter acting to reduce or entirely eliminate the shock of impact of the carrier rods and friction boxes against their respective end stops. Therefore, the frictional engagement between the boxes and friction rod must be very strong, resulting in further wear between the parts and requiring more frequent adjustments to maintain said pre-determined operating relationship.

Heretofore, in order to prevent slippage of the friction box on the friction rod at the start of a reciprocating movement, a drive means, connected to the shock absorber mechanism, was provided for positively accelerating the friction boxes and carrier rods associated therewith to full speed. This drive means while overcoming the initial slipping of the friction boxes on the friction rod was only effective in its operation to a width slightly less than the narrowest part or toe width of a stocking fabric for a conventional looped toe stocking. However, the present trend is to the production of stockings having the toe narrowed to substantially a point thereby permitting the toe to be closed by the usual back seam and eliminating the necessity of a separate looping operation as heretofore.

It is therefore an object of the invention to provide a positive drive means for initiating the

2

reciprocating movement of a friction box to drive a yarn carrier rod in the production of a stocking blank knitted substantially to a point.

Another object of the invention is to provide a positive means for starting the reciprocating movement of a friction box to drive a yarn carrier which is connected to a shock absorber means in such manner that the desired timing of the parts is maintained.

A further object of the invention is to provide means to inactivate the positive drive means with respect to the friction box whereby the friction box may continue to drive a yarn carrier rod within the effective limits of movement of the positive driving means.

With these and other objects in view which will become apparent from the following detailed description of the illustrative embodiment of the invention shown in the accompanying drawings, the invention resides in the novel elements, features of construction and cooperation of parts in cooperative relationship, as hereinafter more particularly pointed out in the claims.

In the drawings:

Fig. 1 is an elevational view of the invention as applied to a portion of a full-fashioned knitting machine and as seen from the front thereof;

Fig. 2 is a top plan view of the mechanism shown in Fig. 1;

Fig. 3 is an end elevational view of the mechanism looking in the direction of the arrows 3—3 of Fig. 1;

Fig. 4 is a cross-sectional view taken substantially along the line 4—4 of Fig. 1;

Fig. 5 is a cross-sectional view taken substantially along the line 5—5 of Fig. 4;

Fig. 6 is a detailed view of certain of the parts of Fig. 4 looking from the left of said figure.

Fig. 7 is a cross-sectional view taken on the line 7—7 of Fig. 6;

Fig. 8 is a cross-sectional view taken substantially on the line 8—8 of Fig. 4;

Fig. 9 is an elevational view taken substantially on the line and looking in the direction of the arrows 9—9 of Fig. 4;

Fig. 10 is a plan view of the mechanism shown in Fig. 9;

Fig. 11 is a view partly in elevation and partly in section and taken substantially on the line 11—11 of Fig. 9;

Fig. 12 is a view similar to a portion of Fig. 10, certain parts being omitted in order to more clearly show others; and

Fig. 13 is a diagrammatic view showing the

relative positions of the parts according to the invention at the start of a driving movement of a yarn carrier rod.

In the drawings and description, only the means necessary to a complete understanding of the invention are specifically set forth; further information as to the construction and operation of other related, usual and well known, knitting machine elements, etc., may be found in one or more of the following publications of the Textile Machine Works, Reading, Pa.:

"The "Reading" Full-Fashioned Knitting Machine Parts Catalog, published in 1940, the supplement thereto, published in 1940, entitled The "Reading" High Production Full-Fashioned Knitting Machine, and the "Reading" Full-Fashioned Knitting Machine Parts Catalog published in 1947.

The apparatus shown in the drawings includes in addition to the usual carrier rods, end stops therefore, friction box and friction rod; a driving bar connected to and driven at the same speed as the friction rod and a driving head mounted on the driving bar. The driving head is provided with means for engaging the head to the driving bar in a manner to prevent substantial slippage between the bar and the head. Means are provided to disengage the driving head from the bar, such disengaging means being connected to a shock absorber means which operates the disengaging means to retard the speed of and stop the driving head. The disengaging and stop means comprises a separate device for controlling the movement of the driving head in opposite directions, the separate devices being connected to the carrier rod end stops for movement toward each other as the width of a fabric is reduced. A connection between the driving head and the friction box serves to accelerate the friction box and carrier rod to full speed near the start of a reciprocating movement and to slow the box and rod down near the end of the reciprocation to reduce or to prevent the shock of impact against the end stops. This arrangement is the same as that shown and described in detail in the patent of Gottlob Bitzer et al., No. 2,637,183, issued May 5, 1953, and of which I am a co-inventor.

The apparatus within the invention includes means to discontinue both the accelerating and shock absorbing action of the driving head on the friction box. For this purpose the driving head is provided with a portion movable out of the path of the stop devices for the driving head to permit the continued movement of the stop devices and the carrier rod end stops toward each other. During this continued movement of the stops toward each other the friction rod becomes the sole driving means for the friction box and carrier rod. However, the reciprocating movement of the friction box at this time is considerably less than the movement necessary to accelerate the friction rod to full speed. Therefore, the friction box and carrier rod only attain a fraction of the normal full speed, thereby eliminating the necessity of further reducing their speed before engaging the end stops.

Referring to Figs. 1 and 3 of the drawings, parts of a usual full-fashioned knitting machine are shown including a high or full speed friction rod 25 and a slow speed friction rod 26. A crosshead 29, fixed to the rod 25, is connected by a link 30 to a coulier arm 31 forming a part of the usual coulier mechanism of the machine (not shown) for driving the rod 25. Friction boxes such as 38 are carried on and frictionally driven by the fric-

tion rods 25 and 26 in the usual manner, said boxes 38 being connected to carrier rods 39, one of which is diagrammatically shown in Fig. 13, to reciprocate them between end stops 40 carried on nuts 41. The nuts 41 are carried on threaded spindles 44 which are turned by means (not shown) to move the nuts toward and away from each other to narrow and widen stocking fabrics in the usual manner.

To facilitate movement of the friction box 38 with the friction rod 25 and to prevent relative movement between the box and friction rod at the start of a reciprocating movement of the rod, additional driving means is shown. Such means includes brackets 45 secured to the friction rod 25 and to a driving member or bar 46 (Figs. 1, 2, 3 and 4), the bar thereby being moved at the same speed as the friction rod 25. Mounted on the driving bar 46 for movement therewith is a driving head 49 having releasable means (Fig. 5) for engaging and disengaging the driving head to and from the driving bar. Said releasable means comprises a block 51 which is secured in a recess in the driving head 49 in contact with the driving bar 46. Block 51 is provided with recesses 54 and 55 open to the underside of bar 46 as shown in Fig. 5. The surfaces forming the bottom walls of recesses 54 and 55 are inclined downwardly toward each other and the center of the head 49. Each recess is provided with a roller element 56 which, through gravity, tends to move down the inclined surfaces away from the driving bar 46 and this movement is opposed by spring pressed plungers 59. The plungers 59 normally tend to press the rollers into contact with both the bar 46 and the inclined bottom walls of recesses 54 and 55. Therefore, as driving bar 46 starts to move either to the right or left, as viewed in Fig. 5, the contact between the one roller, the inclined surface in the corresponding recess of the block and the bar causes the roller to be wedged tightly between the bar and block 51, thereby firmly but releasably engaging the head 49 to the bar. With the part so engaged the head 49 is adapted to positively accelerate one or more friction boxes and the carrier rods connected thereto in the manner hereinafter set forth. The same movement of the bar 46 causes the other roller 56 to ride down the inclined surface to disengage said other roller from the bar 46. Block 51 is also provided with tappet members 60 between the ends of the block and rollers 56 which act to disengage the rollers and therefore the head 49 from the bar 46. Means for operating the tappet members 60 also forms, in the mechanism shown herein, a part of the means for retarding the movement of the head 49 and friction boxes 38 as hereinafter set forth.

Means for transmitting an accelerating force from the driving head 49 to one or more friction boxes 38 includes a rod 61 having a member 64 secured thereto, as shown in Fig. 8. The member 64 is connected to head 49 by means of a pin 65 which is provided with intentional weak spots (Fig. 7) easily sheared when movement of either the driving head 49 or rod 61 is obstructed in relation to the other. The rod 61 carries blocks or collars 66 and 67 between which is positioned a tongue 69 of one of the friction boxes 38, as shown in Fig. 13. The tongue 69 is diagrammatically shown as a part of the friction box. However, in practice the tongue is pivoted on the box whereby it is movable from an active position between the collars 66 and 67 to an inactive position above the path of the collars

to prevent interference between the tongue and the collars when the friction box 38 is disconnected from the friction rod 25. As shown in Fig. 13, the collars 66 and 67 are positioned on the rod 61 to provide a slight clearance between one or the other of the collars and the tongue 69. The slight clearance between one or the other of the collars 66 and 67 and tongue 69 permits the auxiliary friction box 110 to maintain pressure against the rod 61 to hold the rod at the limit of its movement in either direction until the direction of its movement is reversed as more fully set forth in said Patent No. 2,673,183.

As heretofore set forth, a carrier rod 39 is driven by a friction box 38 between end stops 40 carried on the nuts 41. In order to reduce the pressure exerted by a friction box 38 on its carrier rod after the carrier rod has engaged its end stop and while the friction rod 25 continues to slip through the box, the tongue 69 of the box engages stops 70 and 71 (Fig. 13). Stops 70 and 71 are carried on rods or bars 74 and 75, respectively, rod 74 being connected to the left nut 41 and rod 75 being connected to the right nut. The tongue 69 is adapted to engage one of stops 70 or 71 at the same instant that the carrier rod 39 engages its end stop 40.

The usual full-fashioned knitting machine also includes shock absorbing means, for reducing the impact of the carrier rods 39 against the end stops 40 to eliminate the noise and other deleterious effects caused when the carrier rods engage the end stops at full speed. In the present instance, the shock absorbing means is combined with the driving head 49 forming part of the friction box accelerating means disclosed herein. The means shown for this purpose also includes means for disengaging the roller elements 56 of the driving head from the driving bar 46. The means shown for disengaging the roller elements 56 comprises blocks 76 and 77 (Figs. 1, 2 and 13) which are slidably mounted on a bar 79 and positioned at opposite ends of the path of movement of driving head 49. The positions of blocks 76 and 77 are controlled by the rods 74 and 75, respectively, which are connected to the end stops 41 as previously explained, the blocks 76 and 77 being connected to the rods 74 and 75 as hereinafter set forth. The shock absorbing or retarding action of the blocks 76 and 77 is governed by a cam 80 which is reciprocated at approximately half the speed of the bar 46 and the friction rod 25. The means for reciprocating the cam 80 includes a head 81 secured to said cam and slidably mounted on a bar 84, the head 81 being connected by a link 85 to a rocker arm 86 (Fig. 1) which is in turn connected to the coulier mechanism in the usual manner.

The cam 80 has a low control portion 89 and high end portions 90 connected to the low portion by inclined portions 91. Cam 80 controls blocks 76 and 77 by lever systems 94 which are the same except that one is reversed with respect to the other. Each of the lever systems is connected to block 76 or 77 by means of a link 95 (Fig. 1) which is pivoted to a lever 96 fixed to one end of a shaft 99. The shafts are journaled in a left hand head or carriage 100 or a right hand head or carriage 101 slidably mounted on a bar 104 fixed to the frame of the machine. The other end of each shaft 99 has fixed thereto one end of a lever 105, the other end of which rotatably carries a cam follower 106 for engagement with the cam 80. When a cam fol-

lower 106 is on a high portion of the cam 80, the block 76 or 77 is moved toward the driving head 49. As the cam 80 and driving head 49 moves toward the right, the follower 106 moves down the inclined portion 91, connecting the high and low portions 90 and 89, respectively, and thereby moves the block 77 in the same direction as the driving head but at a slower speed than said driving head. Shortly after the block 77 starts moving, the right tappet member 60 (Fig. 5) in the driving head 49 overtakes and engages a contact screw 109 adjustably carried in the block 77. As the driving head 49 continues to move at a faster speed than the block 77, the tappet 60 forces the right roller element to the left out of wedging position to disengage the driving head 49 from the driving bar 46. Immediately upon release of the right roller 60, the driving head 49 is carried along by the rod 61 which is driven at this time by an auxiliary friction box 110 (Fig. 13) on the friction rod 25.

The auxiliary friction box 110 is connected to the rod 61 by the collar 67 and a collar 111 on the rod which are positioned at opposite sides of and in juxtaposed relation to a tongue 114 on the auxiliary friction box 110 so as to prevent lost motion between the box and the rod. The driving head 49 continues to move at a faster speed than the block 77 through the auxiliary friction box 110 until the driving head engages a stop screw 115 also adjustably carried in the block 77 after which the driving head is carried along by the box 110 at the speed of the block. As the speed of the block 77 is reduced, the speed of the rod 61 and the auxiliary friction box 110 is also reduced and the friction box 38 which is still moving with and at the same speed as the friction rod 25, overtakes and engages the collar 66, thereby reducing the speed of the box 38 to that of the rod 61.

Further, as follower 106 continues to move down the inclined portion 91 of the cam 80, shaft 99 and levers 96 and 105 gradually turn in the counterclockwise direction, thereby gradually reducing the speed of the block 77, the driving head 49, the rod 61, friction boxes 38 and 110 and the carrier rod 39. The reduction in speed continues as the follower 106 approaches the low portion, so that the head 49, friction box 38 and the carrier rod 39 is moving very slowly when the tongue 69 of the box 38 engages the stop 71 and the carrier rod engages its end stop 40. The relationship is the same between the driving head 49, block 76 and stop 70 when the driving head moves toward the left and approaches the block 76.

As shown in Fig. 3, the rod 74 is connected to the carriage 100 by means of a bracket 116 and the carriage is connected to the block 76 by means including a link 95 and lever 96. The rod 75 is connected to the carriage 101 by a bracket (not shown) and the carriage 101 is connected to the block 77 by means including a link 95 and lever 96, as more fully shown and described in said Patent No. 2,637,183.

As hereinbefore set forth, the rods 74 and 75 are connected to and move with the left and right nuts 41, respectively, during fashioning movements of the machine. Movement of the rods 74 and 75, also move the stops 70 and 71 for the friction box 38 and the blocks 76 and 77. Therefore, as the fabric is narrowed, the nuts 41 are gradually moved toward each other, which moves the stops 70 and 71 and the blocks 76 and 77 toward each other to reduce the stroke

of the friction box 38 and the driving head 49, respectively. Continued movement of the nuts 41 toward each other will cause the contact screws 109 in blocks 76 and 77 to engage the left and right tappet members 60 to maintain both roller elements 56 disengaged from the driving bar 46. Continued movement of the blocks 76 and 77 toward each other would also cause the stop screws 115 carried in the blocks 76 and 77 to contact opposite ends of the driving head 49, which would prevent further movement of the blocks and nuts toward each other. Therefore, means must be provided to permit continued movement of the blocks 76 and 77 toward each other to reduce the fabric to its narrowest width.

The means for this purpose includes a member 119 fixed to a shaft 120 pivoted in the driving head 49, as shown in Figs. 4, 6 and 7. The member 119 is provided with arms 121 and 124 the inner facing surfaces of which engage a portion 125 of the driving head 49 (Fig. 6). The outer ends of the arms 121 and 124 are normally biased into alignment with the stop screws 115 in the blocks 76 and 77, respectively, by a spring 126, this position of the arms being determined by engagement of a projection 129 on the arm 121 with a surface 130 on the driving head 49 (Fig. 4). The member 119 rotatably carries a follower 131 which is adapted to be engaged by a cam portion 134 of a link 135 to turn the member 119 clockwise to move the arms 121 and 124 out of the path of the stop screws 115, as shown in Fig. 4. One end of link 135 is pivoted at 136 to a lever 139 and the other end of the link is pivoted at 140 to a lever 141, as shown in Figs. 9 and 10. Levers 139 and 141 are pivotally carried on pins 144 and 145, respectively, (Figs. 9, 10 and 12) fixed in a bracket 146 slidably carried on the bar 104. The bracket 146 is normally biased to the right, as viewed in Fig. 9, against a pin 148 in the bar 104, by means of a spring 149, one end of which is connected to the bracket and the other end to said pin.

The lever 139 is provided with a cam member 150 which is adapted to engage a cam member 151 fixed on a bracket 154 also slidably carried on the bar 104. Bracket 154 is normally biased to the left, as viewed in Fig. 9, against a pin 155 in the bar 104, by a spring 156 which is connected between the bracket 154 and pin 155.

At the start of a stocking knitting operation, the nuts 41, stops 70 and 71 and carriages 100 and 101 are spaced the greatest distance from each other. At this time the brackets 146 and 154 are biased against the pins 148 and 155, respectively, and the cam member 150 on lever 139 is positioned to the left of cam member 151 on bracket 154. Also at this time, the levers 139 and 141, the link 135 and cam member 150 is biased to the left, as viewed in Fig. 11, by a spring 159, the left position of the part being determined by engagement of a stop screw 160 with a portion 161 of pin 144 (Fig. 10). The portion 161 of pin 144 also acts as an anchor for one end of the spring 159, the other end of the spring being connected to the lever 141. As the fabric is narrowed the nuts 41 and carriages 100 and 101 are moved closer to each other and the stop screws 115 are moved closer to the arms 121 and 124 on the driving head 49. Just prior to the point at which the stocking is narrowed to simultaneously engage the screws 115 with the ends of arms 121 and 124, the car-

riage 100 engages the bracket 154 and the carriage 101 engages the bracket 146. As the carriages 100 and 101 continue to move toward each other, the brackets 146 and 154 are also moved toward each other to engage the high surfaces of cam members 150 and 151, thereby moving the levers 139—141 and the link 135 to the right to the position of Figs. 4 and 11. The follower 131 on member 119, being positioned in the path of the cam portion 134 of link 135, is engaged and turns the member 119 clockwise to the position of Fig. 4, thereby moving the ends of arms 121 and 124 from the path of stop screws 115 in the blocks 76 and 77. Continued movement of the blocks 76 and 77 toward each other is therefore unobstructed.

When the member 119 is in its inactive position of Fig. 4, the screws 109 in blocks 76 and 77 are in engagement with both tappet members 60, thereby holding the roller elements 56 disengaged from the driving bar 46. As narrowing of the fabric continues, the continued movement of the contact screws 109 toward each other only acts to further depress the plungers 59 through the tappet members 60 and roller elements 56. Also at this time the carrier rods 39 are driven by the friction box 38 and the driving head 49 and rod 61 is reciprocated by the auxiliary friction box 110. As both friction boxes 38 and 110 are driven by the friction rod 25 at the same speed, the rod 61 no longer acts to retard the friction box 38. However, as the stroke of the carrier rod 39 is very short and is actually started and completed in the first or slowest part of the accelerating movement of the friction rod 25, the carrier rod engages the end stops 40 with a reduced impact, thus requiring no further shocking or retarding action. Also, when the member 119 is in inactive position, the reciprocating movement of the driving head 49 is controlled by engagement of either collar 63 or 67 with the tongue 69 of the friction box 38.

Of course, the improvements specifically shown and described, by which the above described results are obtained, can be changed and modified in various ways without departing from the invention herein disclosed and hereinafter claimed.

I claim:

1. In a full-fashioned knitting machine, the combination with a friction rod, yarn carrier rods and a box having frictional engagement with said friction rod for reciprocating said yarn carrier rods, of a driving head, means connected to said driving head for transmitting a driving force from said driving head to said box, stop means for said driving head and means for inactivating said stop means relative to said driving head.

2. In a full-fashioned knitting machine, the combination with a friction rod, yarn carrier rods and a box having frictional engagement with said friction rod for reciprocating said yarn carrier rods, of a driving head, means connected to said driving head for transmitting a driving force from said driving head to said box, stop means for said driving head, contact means on said driving head normally positioned to be engaged by said stop means and means for moving said contact means and stop means to inactive position relative to each other.

3. In a full-fashioned knitting machine, the combination with a friction rod, yarn carrier rods, a friction box on said friction rod for

reciprocating said yarn carrier rods and movable end stops for said yarn carrier rods and friction box, of a driving head, means connected to said driving head for transmitting a driving force from said driving head to said friction box, stop devices for said driving head, contact means on said driving head normally in an active position to engage said stop devices to limit the reciprocating movement of said driving head and means controlled by the position of said end stops for determining the active and inactive positions of said contact means relative to said stop devices.

4. In a full-fashioned knitting machine, the combination with a friction rod, yarn carrier rods, a friction box on said friction rod for reciprocating said yarn carrier rods and end stops movable toward each other for controlling the reciprocating movement of said carrier rods and friction box, of a driving head, means connected to said driving head for transmitting a driving force from said driving head to said friction box, stop means for said driving head, contact means on said driving head normally in position to engage said stop means to limit the reciprocating movement of said driving head, and means controlled through the movement of said end stops toward each other for moving said contact means to inactive position relative to said stop means.

5. In a knitting machine having a friction rod, yarn carrier rods, a box having frictional engagement with said friction rod for reciprocating said yarn carrier rods, a driving head, means for reciprocating said driving head, means connected to said driving head for transmitting a driving force from said driving head to said box, stop devices for said driving head, said stop devices being movable toward each other to vary the reciprocating movement of said driving head, contact means on said driving head normally positioned to engage said stop devices during reciprocating movements of said driving head, and means controlled through the movement of said stop devices toward each other for moving said contact means to inactive positions relative to said stop devices.

6. In a knitting machine having a friction rod, yarn carrier rods, a friction box on said friction rod for reciprocating said yarn carrier rods, end stops movable toward each other for said carrier rods and friction box, a driving head, means connecting said driving head for transmitting a driving force from said driving head to said friction box, stop devices for said driving head, means connecting said stop devices to said end stops, contact means on said driving head normally positioned to be engaged by said stop de-

vices and cam means operated by the movement of said end stops toward each other for moving said contact means to inactive position relative to said stop devices.

- 5 7. In a knitting machine having a friction rod, yarn carrier rods, a friction box on said friction rod for reciprocating said yarn carrier rods, end stops for said carrier rods and friction box, a driving head, means connected to said driving head for transmitting a driving force from said driving head to said friction box in addition to the driving force exerted by said friction rod on said friction box, stop devices for said driving head and means connecting said stop devices to said end stops, a pivoted member on said driving head normally positioned to be engaged by said stop devices, a cam member, a second cam member normally disengaged from said first cam member and connections between said first and 10 second cam members and said end stops whereby said first and second cam members are moved into engagement as said end stops are moved toward each other to move said pivoted member to inactive position relative to said stop devices.
- 15 20 25 8. In a full-fashioned knitting machine having a friction rod, yarn carrier rods, a friction box on and driven by said friction rod for reciprocating said carrier rods, end stops for said carrier rods and friction box, said end stops being movable toward each other to reduce the reciprocating movement of said carrier rods and friction box, a driving head, means connected to said driving head for transmitting a driving force from said driving head to said friction box in addition to the driving force exerted by said friction rod on said friction box, stop devices for said driving head, a bar, connecting means between said end stops and stop devices slidable on said bar, said connecting means being adapted 30 35 40 45 to move said stop devices toward each other with said end stops, a pivoted member on said driving head normally in position for engagement by said end stop devices, a first cam slidable on said bar, a second cam slidable on said bar, said first and second cams being moved into engagement by said connecting means to move said pivoted member to inactive position relative to said stop devices.
